UNITED STATES PATENT OFFICE

125,308

DESIGN FOR A COMBINED BICYCLE TANK AND FRAME

Horace M. Huffman, Jr., Dayton, Ohio, assignor
to The Huffman Manufacturing Company, Day-
ton, Ohio, a corporation of Ohio

Application December 28, 1939, Serial No. 89,175

Term of patent 3½ years

To all whom it may concern:

Be it known that I, Horace M. Huffman, Jr., a citizen of the United States of America, residing at Dayton, in the county of Montgomery and State of Ohio, have invented a new, original, and ornamental Design for a Combined Bicycle Tank and Frame, of which the following is a specification, reference being had to the accompanying drawing, forming a part thereof, and in which

Fig. 1 is a side elevational view of the combined bicycle tank and frame showing my new design;

Fig. 2 is a side elevational view on a larger scale of the tank shown in Fig. 1;

Fig. 3 is a plan view of the tank as shown in Fig. 2; and

Fig. 4 is a sectional view on the line 4—4 of Fig. 2.

The dominant feature of my design resides in the part shown in full lines in the drawing.

I claim:

The ornamental design for a combined bicycle tank and frame, substantially as shown and described.

HORACE M. HUFFMAN, JR.
